CLAIM

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof;

FIG. 3 is a third image thereof;

FIG. 4 is a second embodiment of a display screen or portion thereof with animated graphical user interface showing a first image of the claimed design;

FIG. 5 is a second image thereof;

FIG. 6 is a third image thereof;

FIG. 7 is a third embodiment of a display screen or portion thereof with animated graphical user interface showing a first image of the claimed design;

FIG. 8 is a second image thereof;

FIG. 9 is a third image thereof;

FIG. 10 is a fourth embodiment of a display screen or portion thereof with animated graphical user interface showing a first image of the claimed design;

FIG. 11 is a second image thereof; and,

FIG. 12 is a third image thereof.

The outermost dashed broken lines in the figures show a display screen or portion thereof, and form no part of the claimed design. The other dashed broken lines in the figures show portions of the animated graphical user interface that form no part of the claimed design. The dot-dash broken lines in the figures and the areas within the dot-dash broken
